ELECTRICAL SWITCH ENCLOSURE

Carl W. Sundberg, Birmingham, Mich., assignor to Square D Company, Detroit, Mich., a corporation of Michigan

Application September 15, 1955, Serial No. 37,954

Term of patent 14 years

(Cl. D26—13)

Fig. 1

Fig. 2

Fig. 3

Figure 1 is a front elevational view of an electrical switch enclosure showing my new design.

Figure 2 is a side elevational view.

Figure 3 is a bottom plan view thereof.

The dominant features of my design reside in the portions shown in full lines.

I claim:

The ornamental design for an electrical switch enclosure, substantially as shown, and described.
